UNITED STATES PATENT OFFICE.

JOHN DE LEO, OF NEW YORK, N. Y.

DESIGN FOR A CANDLE CUP FOR LIGHTING FIXTURES.

Application filed July 28, 1924. Serial No. 10,269. Term of patent 7 years.

To all whom it may concern:

Be it known that I, JOHN DE LEO, a citizen of the United States, residing in New York, in the county of New York and State of New York, have invented a new, original, and ornamental Design for a Candle Cup for Lighting Fixtures, of which the following is a specification, reference being had to the accompanying drawing, forming part thereof.

Figure 1 is a top plan view of the cup. Figure 2 is a side elevational view thereof. Figure 3 is a bottom plan view of the same.

I claim:—

The ornamental design for a candle cup for lighting fixtures as shown.

JOHN DE LEO.
